UNITED STATES PATENT OFFICE.

JOSEPH BLOOM, OF NEW YORK, N. Y.

STITCH WHEEL FOR KNITTING MACHINES.

Application filed July 10, 1923. Serial No. 650,716.

To all whom it may concern:

Be it known that I, JOSEPH BLOOM, a citizen of the United States, and a resident of the city of New York, borough of Manhattan, in the county and State of New York, have invented a new and Improved Stitch Wheel for Knitting Machines, of which the following is a full, clear, and exact description.

10 The present invention relates to new and useful improvements in knitting machines and it pertains more particularly to a new and improved stitch wheel therefor.

Stitch wheels as ordinarily constructed 15 have a plurality of stationary blades which pass between the needles of the circular series to form the stitch loops. Due to the angle at which these blades enter and leave the spaces between the needles, the distance 20 between the needles which the blades may move and the consequent size of the loops formed by the stitch wheel is limited.

It is one of the primary objects of the invention to provide a new and improved 25 stitch wheel, the use of which permits of the formation of larger loops.

It is a further object of the invention to construct the stitch wheel in such a manner that loops of different sizes may be formed.

30 With the above and other objects in view, reference is had to the accompanying drawings, in which—

Figure 1 is a sectional view of a stitch wheel constructed in accordance with the 35 present invention, the blades of the wheel being shown in elevation;

Fig. 2 is a plan view of the wheel with a portion of the blades removed;

Fig. 3 is a plan view of the stitch wheel 40 support;

Fig. 4 is a perspective view of one of the blades employed in one of the stitch wheels;

Fig. 5 is a view partly in elevation and partly schematic, of a stitch wheel constructed in accordance with the present invention;

Fig. 6 is a perspective view of one of the blades, the view having been taken at a different angle than that shown in Fig. 1;

50 Fig. 7 is a perspective view showing the manner in which the blades of the improved stitch wheel pass between the needles of the circular series;

Fig. 8 is a top plan schematic view showing the manner in which the blades of the

improved stitch wheel pass between the needles of the circular series.

Referring again to the drawings, the reference character 10 designates a suitable support, and such support is provided with an 60 opening 11. Projecting through the opening 11 is a spindle 12, and such spindle also projects through a member 13 which has an extension 14 mounted in the opening 11. This member 13 is secured to the spindle 65 12 by means of a key, or the like, 15. The lower end of the spindle 12 is screw-threaded, as at 16, and receives a nut 17, by means of which the support 10 is clamped between the member 13 and the nut 17. The member 70 13 is provided with a flange 18, and said flange 18 has an eccentric portion 19, the purpose of which will be hereinafter described. The member 13 and spindle 12 are immovable with respect to the support 10 75 by means of the nut 17.

The reference character 20 designates the hub member of a stitch wheel, and the body portion 21 of the stitch wheel surrounds the hub member 20 and is secured thereto by 80 means of bolts, cap screws, or the like, 22. The stitch wheel is prevented from movement longitudinally of the spindle 12, by a cross key 23. The body portion 21 of the stitch wheel is provided with a plurality of 85 angularly disposed slots 24, and mounted in each of these slots 24, is a blade 25. The blades 25 are adapted for swinging movement, and are pivotally mounted upon ring 26, which ring lies in an annular channel 90 formed in the body portion of the stitch wheel, and intersecting the slots 24.

By reference to Figs. 4 and 6, it will be seen that each of the blades 25 comprises a body portion 27 of substantially triangular 95 form. One of the corners of each triangular blade is provided with a hook 28, another corner with a projecting finger 29, and the third corner with a substantially right-angularly disposed bifurcated projection 30. 100 This bifurcated projection 30 is more clearly shown in Fig. 4. The hook portion 28 of each of the blades 25 is adapted to engage the ring 26 heretofore mentioned for pivotally supporting the blades in their respective slots 24.

The projecting finger 29 of the blades is adapted to pass between the needles of a circular series in a circular knitting machine.

When the stitch wheel is assembled or po- 110

sitioned upon the spindle 12, the furcations of the bifurcated projection 30 are adapted to engage the flange 18 of the member 13, as more clearly shown in Fig. 1. When the 5 stitch wheel is thus assembled, upon rotation of the circular series of needles, the projection 29 of each of the blades 25 will be caused to pass between the needles of the circular series as clearly shown in Figs. 7 10 and 8, the needles of the circular series being designated by the reference character 31. The eccentric portion 19 of the flange 18 is so positioned with respect to the needles 31 of the circular series, that as the blades 15 25 pass around the spindle 12 and between needles 31, when the blades 25 are in alignment with the radius of the circle upon which the needles 31 are arranged, the blades 25 will be projected to their limit, as designated 20 by the reference character A in Fig. 8. As the blades pass through the spaces between the needles of the circular series, the projecting finger 29 carries the thread through such spaces in the ordinary manner, as more clearly shown in Fig. 7.

From the foregoing it is apparent that the distance to which the blades are projected between the needles and the size of the loop (which is designated in Fig. 8 by 30 the reference character B) formed thereby, is determined by the degree of eccentricity of the eccentric portion 19. Therefore, by varying the pitch or degree of eccentricity of the eccentric portion 19, loops of various 35 sizes may be obtained. It is therefore apparent that the present invention provides a stitch wheel, the use of which permits of larger loops being obtained in circular knitting machines than is possible where the 40 blades of the stitch wheel are rigidly mounted and have no pivotal movement, since the pivotal movement permits of their moving relative to the needles of the circular series to permit of the ready insertion and withdrawal of the blades with respect to the 45 spaces between the needles of the circular series.

I claim:

1. A rotary burr wheel for use with knitting machines of the united needle type, 50 said burr wheel comprising a plurality of substantially triangular plates having an attaching hook on one corner, a loop sinking nose on another corner, and a bifurcated lug upon the third corner. 55

2. A rotary burr wheel having a body formed of a plurality of pivotally suspended substantially triangular plates, each of which has an attaching hook on one corner, a loop sinking nose on another corner, and a bifurcated guide on the third corner, and 60 means for engagement with the bifurcated guide for determining the pivotal movement of said pivotally suspended plates about their point of attachment. 65

3. A rotary burr wheel for knitting machines of the united needle type, said burr wheel comprising a body portion of pivotally mounted triangular blades, each of which consists of a substantially triangular 70 body member having a supporting hook on one corner, a loop sinking nose on a second corner, and a bifurcated guide on the third corner, said bifurcated guide being angularly disposed with respect to the body of 75 the blade.

4. In a knitting machine, a burr wheel comprising a hub member, a plurality of substantially triangular blades pivotally connected at one of their corners in said hub member, a loop sinking nose formed on a second corner of said substantially triangular blades, a bifurcated guide member formed on the third corner of said substantially triangular blades and occupying a 85 plane below and substantially in alignment with the pivotal mounting of said blades when the latter are in their normal position, and a cam guide having engagement with said bifurcated guide members to determine the extent of pivotal movement of the blades about their point of pivotal suspension. 90

JOSEPH BLOOM.
